UNITED STATES PATENT OFFICE

95,119

DESIGN FOR A TAPESTRY

Jacob Cohen, Philadelphia, Pa.

Application September 11, 1934, Serial No. 53,255

Term of patent 3½ years

To all whom it may concern:

Be it known that I, Jacob Cohen, a citizen of the United States, residing at Philadelphia, in the county of Philadelphia and State of Pennsylvania, have invented a new, original, and ornamental Design for a Tapestry, of which the following is a specification, reference being had to the accompanying drawing, forming part thereof.

The figure is a face view of the tapestry, showing my design.

The design includes a space for a picture of an individual, on the rug enclosed within the representation of a frame.

I claim:—

The ornamental design for a tapestry, as shown and described.

JACOB COHEN.
